UNITED STATES PATENT OFFICE.

ARCHIBALD BANNATYNE, OF WATERBURY, CONNECTICUT, ASSIGNOR TO
THE WATERBURY CLOCK COMPANY, OF SAME PLACE.

ALARM-CLOCK.

SPECIFICATION forming part of Letters Patent No. 399,725, dated March 19, 1889.

Application filed July 16, 1887. Serial No. 244,500. (Model.)

To all whom it may concern:

Be it known that I, ARCHIBALD BANNATYNE, residing at Waterbury, in the county of New Haven and State of Connecticut, have 5 invented certain new and useful Improvements in Alarm-Clocks; and I do declare the following to be a full, clear, and exact description of the same, reference being had to the accompanying drawings, which form a part 10 of this specification.

My invention relates to an improvement in single-spring alarm-clocks, the object being to provide for unlocking the alarm-train independent of any interference with the main-spring, reducing the resistance to the time-train to the minimum, completely retiring the alarm-train when desired, running down the mainspring independent of the time-train, and for making the clocks cheaper, simpler, 15 more compact, easier to operate, and more reliable in use.

With these ends in view my invention consists in a single-spring alarm-clock having stop-work entirely independent of the time-train and adapted for direct manual operation 20 in unlocking the alarm-train for action when such alarm-train is released by the time-train.

My invention further consists in certain details of construction and combinations of 25 parts, as will be hereinafter described, and pointed out in the claims.

In the accompanying drawings, Figure 1 is a view in front elevation of a clock embodying my invention. Fig. 2 is an enlarged plan view thereof. Fig. 3 is a view of the clock in elevation with the front plate removed. Fig. 4 is a broken view in elevation, showing the combined stopping and unlocking mechanism. Fig. 5 is an enlarged plan view of the novel 35 features, and Fig. 6 is an enlarged perspective view of the push-staff and its lever.

As herein shown, the time-train, the alarm-train, and the combined stopping and unlocking mechanism are mounted between and 40 upon two circular frame-plates, A and B, between which is included the mainspring C driving both trains.

The time-train, as herein shown, consists of a wheel, D, pinion E, wheel F, pinion G, 45 wheel H, pinion I, wheel J, escape-pinion K, and escape-wheel L, the latter being engaged

by an anchor-shaped pallet, M, the staff whereof carries an arm, N, engaging with the pin O of the balance-wheel P, which is controlled by the spring Q, as shown. 55

The alarm-train consists of an alarm main wheel, R, an alarm first pinion, S, an alarm second-wheel, T, an alarm second-pinion, U, and an alarm escape-wheel, V, as shown. A verge, W, engaging with such escape-wheel, is 60 secured to a verge-staff, X, provided near its center with a bell-hammer, Y, at one end, with a stop-arm, Z, having its free end bent at a right angle, and at the other end with a straight locking-arm, A'. The said stop-arm Z is 65 lifted for locking the verge W into the escape-wheel, and so stopping the alarm-train, by a combined stop and let-off or unlocking-lever B', extending under it and secured to a manual push-staff, C', having 70 bearing in the frame-plates A and B, with a capacity for rotation and endwise play therein, provided upon its inner end with a push-button, D', and encircled by a spiral spring, E', having the twofold function of 75 rotating it to disengage its lever B' from the face of the stop-pin F', when it is manually pushed forward, and of automatically moving it back into line with the said pin and under the arm Z, when the actuation of the 80 alarm-train operates to withdraw the said pin from contact with the face or side of the said lever. The said stop-pin F' is secured to a rotary female stop-piece, G', loosely mounted on a short staff, H', located in the frame-plate 85 B, and rotated always in the same direction by a male stop-piece, I', also always rotated in the same direction and mounted upon the alarm second-wheel staff J', as shown.

The arm A' of the verge-staff X is engaged 90 by the bent finger K' of a flat releasing-spring, L', secured to the outer face of the frame-plate A, which is provided with a small opening, M', through which the said finger projects for engagement with the said locking-arm A'.

The spring L' is located between the frame-plate specified and the inner face of the alarm-dial wheel N', which is provided with a sleeve-cam, O', co-operating with a flat wrought-metal fingered collar, P', made in one piece 100 and located on the alarm set-staff Q', upon

which the wheel N' is loosely mounted. The said alarm-dial wheel N' meshes into the minute-wheel pinion R' , carried by the minute-wheel S' , which meshes into the socket-pinion T' , mounted on the center shaft, U' , located in the time-train and carrying the hour-wheel V' , which meshes into the minute-wheel pinion R' aforesaid.

Having described my invention in detail, I will now set forth the mode of operating it.

The set-staff Q' is first turned to set the alarm to go off at any predetermined time. In this operation the finger of the collar P' , riding upon the sleeve-cam O' , forces the alarm-dial wheel N' , and hence the spring L' , toward the plate B , the finger K' of the spring being brought into position for engagement with the locking-arm A' of the verge-staff. The push-staff C' is then manually pushed forward by its button D' until its lever B' clears the face of the stop-pin F' , when the spring E' at once operates to rotate the push-staff and engage the lever B' with the short staff H' . The spring then operates to push the staff C' back, and in so doing engages the side or face of the lever B' with the end of the stop-pin. This leaves the lever B' below and out of contact with the arm Z of the verge-staff, the alarm-train held by the engagement of the arm A' , with the finger K' of the spring L' and the stop-pin free to be rotated when the alarm-train is released. Then when the time-train actuating the alarm-dial wheel N' brings the drop of the sleeve-cam O' into alignment with the finger of the collar P' the flat spring L' at once recovers and springs away from the plate B , disengaging its finger K' from the arm A' and moving the alarm-dial wheel N' also away from the said plate and on the set-staff Q' . The verge-staff being now entirely free, the alarm-train is released and the alarm given by the impact of the bell-hammer upon a suitable bell. The rotation of the stop-pieces G' and I' , following the actuation of the alarm-train, at once disengages the stop-pin F' from the lever B' , which is then moved back into its normal position under the arm Z by the action of the spiral spring E' , so that when the female stop-piece G' has made one revolution the pin will engage with the lower edge of the lever B' , which it will lift slightly. The lever B' will in turn lift the stop-arm Z sufficiently to turn the verge-staff X and lock the verge into the escape-wheel V , and thus stop the alarm-train, which will now be held by the said stop-arm, the finger K' and the arm A' being still disengaged. Then when the alarm is set again and the said finger K' and arm A' therefore re-engaged the push-staff is pushed forward manually until the lever B' clears the face of the stop-pin F' , leaving the stop-pieces free to rotate when the time-train disengages the spring-finger K' from the arm A' . After setting the alarm then it is simply necessary to push the push-staff button.

To let off or run down the mainspring, the set-staff is turned to bring the finger of the collar P' into alignment with the drop of the cam O' , so as to permit the disengagement of the spring-finger K' of the spring L' from the arm A' carried by the verge-staff. The push-staff is then pushed in to release the stop-pieces for rotation, and so held until the mainspring has run down, which results independent of the time-train and without injury thereto.

It will be noted that under my invention the stop-work is entirely independent of the time-train and adapted for direct manual operation in unlocking the alarm-train for action when such train is released by the time-train, so that not only is no power taken from the time-train to unlock the alarm-train after an alarm has been sounded, but also the setting of the clock to give an alarm is made entirely independent of the winding of the clock. It will be noted, also, that when the stop-work acts to stop the alarm-train it assumes the entire power thereof, which is shifted to it from the time-train, cutting out the alarm-train, as it were, from the clock, which may then be run indefinitely as though it were a simple time-piece and had no alarm attachment. My invention, therefore, by relieving the time-train of resistance, as described, reduces the power required in the mainspring, and therefore makes the clock easier to wind and cheaper to construct. Furthermore, my improved stop-work is positive and therefore reliable in operation and does not involve that liability to error inherent in frictional and spring-controlled alarm mechanisms.

The provision for running down the mainspring is an important feature. It may be done when the clock is in or out of its case and absolutely without injury to the movement. It also avoids the injury which the workman frequently receives in his fingers in running down a mainspring. This feature is not limited to use with alarm mechanisms. Such a simple escape-train as would be left by removing the alarm-dial work and the bell-hammer might be applied to any clock.

Under my invention, also, the bell-hammer is maintained almost rigid and prevented from swinging and striking the bell when the alarm-train is held either by the releasing-spring or by the stop-work, this being effected by holding the train through arms carried by the very staff which also carries the verge and hammer. It will also be noted that, whether the train is locked or unlocked, the power is constantly on the verge, whereby the strain on the train is reduced to the minimum.

The flat-fingered collar co-operating with the sleeve-cam on the alarm-dial wheel is a cheap and reliable substitute for the pin heretofore employed and requiring the drilling of a hole in the staff, which is thereby weakened. Another advantage that the fingered collar has over a pin is that the collar may be ad-

justed back and forth on the staff, so as to place more or less tension on the flat releasing-spring, as desired, whereas a pin located in a hole in the staff cannot be so adjusted. 5 Furthermore, a flat fingered collar has a sharp edge from which the cam may drop abruptly, whereby a more accurate timing of the alarm may be had than with a pin. Again, with a flat fingered collar I get a larger bearing-surface for the edge of the cam to ride upon than can be secured with a pin.

10 My improved mechanism is convenient, reliable of operation, simple, cheap, and compact, and secures to the time-train the maximum of independence from the alarm mechanism, whereby both trains give better and closer performance.

I would have it understood that I do not limit myself to the exact construction shown 15 and described, but hold myself at liberty to make such changes and alterations as fairly fall within the spirit and scope of my invention.

Having fully described my invention, what I 20 claim as new, and desire to secure by Letters Patent, is—

1. In a single-spring alarm-clock, the combination, with a spring, of a time-train and an alarm-train driven thereby, and alarm 25 stop-work for holding the alarm-train, such stop-work being entirely independent of the time-train of the clock and adapted for direct manual operation in unlocking the alarm-train, substantially as set forth.

30 2. In a single-spring alarm-clock, the combination, with a spring, of a time-train and an alarm-train driven thereby, and alarm stop-work having a rotatable and a longitudinally-movable push-staff carrying a lever, through 35 which the alarm-train is automatically locked, the said train being unlocked by manually moving the staff endwise and thus shifting the lever, substantially as set forth.

35 3. In a single-spring alarm-clock, the combination, with a manual push-staff carrying a stop-lever, of a rotary stop actuated from the mainspring and engaging with the said stop-lever, which is disengaged from the stop when the said staff is manually moved endwise, and 40 an arm carried by the verge-staff and engaged by the stop-lever when the same is lifted by the rotary stop, substantially as set forth.

4. In a single-spring alarm-clock, the combination, with a spring-actuated manual push-staff carrying a stop-lever, of male and fe-

male rotary stop-pieces driven by the main-spring, a stop-pin carried by the female stop-piece and rotated in range of the said stop-lever, a stop-arm carried by the verge-staff in position to be operated by the stop-lever, 60 and a locking-arm also carried by such staff and controlled by the alarm-train, substantially as set forth.

5. In a single-spring alarm-clock, the combination, with a spring, of a time-train and 65 an alarm-train driven thereby, and alarm stop-work made entirely independent of the time-train and having two rotary stop-pieces always rotated in the same direction by the alarm-train, which is stopped through them, 70 one of such rotary pieces carrying a pin operating a stop-lever, substantially as set forth.

6. In a single-spring alarm-clock, the combination, with a spring, of a time-train, an alarm-train provided with a verge-staff having 75 a stop-arm and a locking-arm, and alarm stop-work having a push-staff adapted for direct manual operation, and carrying a stop-lever which co-operates with the stop-arm to stop the alarm-train, the said locking-arm being connected with the time-train, which automatically holds and releases it, substantially as set forth.

7. In a clock, the combination, with a spring, of a time-train driven by said spring, an alarm 80 or escape train geared to the said spring and normally cut out of action, and manual let-off or stop mechanism entirely independent of the time-train and manually operated to release the escape-train, whereby the spring 85 may be run down without disturbing the time-train, substantially as set forth.

8. In an alarm-clock, the combination, with the time-train thereof, of a sleeve-cam carried by a wheel driven by such train, an independent rotatable set-staff extending through such cam which rotates around the staff, and a flat collar having a finger projecting from its edge in the same plane therewith, such collar and finger being made from one piece 90 of sheet metal and the finger bearing flatwise on the edge of the cam, substantially as set forth.

In testimony whereof I have signed this specification in the presence of two subscribing witnesses.

ARCHIBALD BANNATYNE.
